[57] CLAIM

The ornamental design for a nozzle, as shown and described.

DESCRIPTION

FIG. 1 is a right side elevational view of the present design, the left side being a mirror image of the right side, the broken line showing the trigger sprayer in FIG. 1 is illustrative of environmental structure only and forms no part of the claimed design;

FIG. 2 is a plan view thereof;

FIG. 3 is a front elevational view; and,

FIG. 4 is a rear elevational view.
